UNITED STATES PATENT OFFICE.

HARRY W. LOCKLEY, OF NEW CASTLE, PENNSYLVANIA, ASSIGNOR TO KELLOGG MANUFACTURING COMPANY, OF ROCHESTER, NEW YORK, A CORPORATION OF NEW YORK.

AIR-PUMP.

1,181,325.

Specification of Letters Patent.

Patented May 2, 1916.

Application filed December 16, 1914. Serial No. 877,575.

To all whom it may concern:

Be it known that I, HARRY W. LOCKLEY, a citizen of the United States, residing at New Castle, in the county of Lawrence and State of Pennsylvania, have invented certain new and useful Improvements in Air-Pumps, of which the following is a specification, reference being had to the accompanying drawings.

10 My invention relates to pumps, and particularly to pumps designed to be used for the inflation of the tires of automobiles.

The primary object of my invention is the provision of a strong, durable, simple and 15 yet highly effective air pump which may be economical to manufacture and in which the parts may be readily assembled or disassembled for repair or replacement.

A further object is the provision of a 20 crank case so formed that it may be cast or otherwise formed in one integral piece, thus preventing leakage in the crank case which is common where the crank case is composed of a plurality of pieces, and permitting of 25 economy in the manufacture of the case.

A further object is to provide in connection with the crank case a cylinder, cast or otherwise formed in one piece together with the valve housing for inclosing the inlet and 30 outlet valves of the pump.

Still another object is to provide an eccentric for operating the piston to thereby secure steadiness of operation and strength, and provide the piston with guide members 35 embracing the eccentric shaft and the eccentric, and holding the piston from lateral motion and in proper alinement with the cylinder, thus securing greater efficiency and durability of the pump by reducing friction 40 and strain.

Still another object of the invention is to so construct the pump that the stroke of the piston may be relatively long in proportion to the diameter thereof, thus reducing strain 45 and tending to permit very free operation of the piston with a relatively high efficiency.

Still another object is to so construct the eccentric and the shaft that the eccentric may be forced or pressed on the shaft, and so that the eccentric and shaft may be readily assembled in a crank case cast or formed in one piece.

Still another object is to provide the crank case with oppositely disposed air inlet open-

ings, and provide means whereby one or the other of the openings may be covered so as to permit the inlet of air to the crank case through an opening so situated with relation to the rotation of the eccentric with- 60 in the crank case that oil will not be thrown out through said opening.

Still another object is to provide means whereby the pump may be readily operatively connected to a driving gear wheel or 65 disconnected therefrom, and provide a shipper lever for this purpose and novel means for holding the shipper lever in its adjusted positions.

Other objects will appear in the course of 70 the following description.

My invention is illustrated in the accompanying drawings, wherein—

Figure 1 is a side elevation of my improved tire pump; Fig. 2 is a vertical section 75 on the line 2—2 of Fig. 3; Fig. 3 is a vertical section on the line 3—3 of Fig. 2; Fig. 4 is a fragmentary section through the arm 42 and the shipper lever; Fig. 5 is a fragmentary section showing one of the air open- 80 ings in the crank case and its cap elevated.

Corresponding and like parts are referred to in the following description and designated in all parts of the accompanying drawings by like reference numerals. 85

Referring to the drawings, 2 designates generally the crank case of my improved pump. This case has the form of a partial cylinder closed at its ends by means of the walls 3 and having a base 4. One end wall 90 3 is provided with an inwardly projecting annular flange 5 and the other end wall is provided with an inwardly projecting flange 5 and an outwardly projecting flange 6. Bearing sleeves 7 are disposed in these open- 95 ings surrounded by the walls 5 and 6, and mounted in these bearing sleeves is the shaft 8.

The upper end of the crank case is open and is formed with an annular flange 9 100 forming an annular seat for the cylinder 10. This cylinder 10 is secured to the crank case in any suitable manner, and is formed at its upper end with an integral valve housing 11. This valve housing is cast with the cylinder 105 and afterward milled out to provide an air inlet passage 12 and an air outlet passage 13, and to form a passage for a valve stem 18 and the valve seat 20, the air passage 12 is milled out only for a portion of the depth 110

- of the valve housing and the web left is drilled out as at 12^a to form holes permitting the passage of air and yet allowing sufficient of the original casting to remain to form a 5 spider supporting the central annular guide 14. The valve passage 13 at its upper end is slightly flared and interiorly screw threaded, the lower end of the valve passage 13 being contracted to form a valve seat. 10 A ball valve 15 normally rests upon this valve seat and is held in place by a spring 16, in turn held in position by engaging against the wall of the flared orifice formed in the lower end of an elbow 17, this elbow 15 being exteriorly screw threaded at opposite ends, one of these ends engaging the screw threads of the valve passage 13, the other being adapted to be connected to any suitable tubular conductor through which the 20 compressed air may be carried to the point where it is desired to house it.

Mounted within the annulus 14 is a valve spindle 18 carrying at its lower end a valve 19 seating upward against the valve seat 20 25 formed at the lower end of the wall surrounding the passage 12. A coiled spring 21 surrounds the annulus 14 and at its lower end bears against the spider supporting this annulus, and at its upper end bears against the washer 22 carried upon the end of the 30 spindle 18 and held in place by a pin 23. The upper end of the air passage 12 is partially closed or covered by means of a cap 24 which is spaced from the upper end of the 35 wall of the valve passage to admit air, but protects the valve passage, and the valve therein from the lodgment of dirt and dust.

Mounted in the bearings formed in the crank case is the shaft 8, as previously 40 stated, and keyed upon this shaft by a key 8^a is the eccentric 25. Mounted upon the eccentric and of course surrounding the same, is an eccentric ring or band 26 which has formed with it the radially projecting 45 lug 27. This lug is perforated for the passage of the wrist pin 28, this wrist pin being held in place by means of a set screw entering the lug 27.

The piston 29 may be of any suitable 50 construction, but is formed with the downwardly projecting laterally spaced members 30 which are vertically slotted as at 31 so as to provide four depending guide fingers 32. The slot 31 is of a size just sufficient to 55 receive shaft 8, so that the walls of the slots 31 will be guided against the shaft 8. The members 30 are spaced apart, as illustrated in Fig. 3, a distance just sufficient to receive between them the eccentric and the eccentric 60 ring. Furthermore, it will be seen from Fig. 3 that the outer faces of these members 30 have sliding engagement with and are guided by the inwardly extending annular flanges 5. By this construction the depending members 30 are so supported that

these depending members will be prevented from having any lateral movement and be prevented from getting out of parallel relation to the longitudinal axis of the cylinder 10, and the piston will be prevented 70 from unequal wear and thus reduce friction and strain. Preferably the members 30 are formed integral with the body of the piston.

It will be noted from Fig. 3 that the upwardly extending walls of the crank case are 75 provided with the inwardly extending flanges 33, and that these flanges, together with the flanges 9, support an annulus of felt or other suitable material, designated 34. These flanges form baffles which 80 tend to keep the oil within the crank case. The felt washer or pad 34 will absorb any small quantities of oil which the baffles have failed to keep in the crank case, and thus this felt ring or washer 34 is kept 85 slightly moist with lubricant. When the piston is lowered it contacts with this compressible ring or washer 34, and the oil from the washer is forced outward at the extremity of the suction stroke of the piston, 90 thus providing for the proper lubrication of the parts.

It will be noted from Fig. 2 that the peripheral wall of the crank case is formed at opposite points with air inlet openings 35. 95 These are for the admission of air to the crank case upon the outward movement of the piston and for the expulsion of air from the crank case upon the inward movement thereof. Removable caps 36 are provided 100 which are engaged with the annular wall surrounding the openings 35, and which one of these caps will be elevated to admit air and which retained in position will depend upon the direction of movement of the eccentric, that cap being retained to close the opening 35 which if removed would permit the oil to be thrown out through the opening 35 upon the rotation of the eccentric. 110 The lower end of the crank case is provided 110 with an oil cup designated 37. This is the only portion of the pump where it is necessary to introduce the lubricant, and this oil cup also provides for overflow and prevents an excess of oil from flowing from the crank 115 case. The caps 36 are held in position by screws 36^a and when it is desired to elevate one of the caps, washers 36^b are disposed between the cap and the face of the crank case.

Splined upon the shaft 8, or mounted thereon in any suitable manner, to turn with the shaft but have longitudinal movement thereon, is a gear wheel 38, as shown most clearly in Fig. 1. This gear wheel carries upon it a collar 39 which surrounds the shaft 8 and is splined to it, this collar being formed with a groove 40. A shipper lever 41 is pivotally mounted astride of an arm 42 extending outward from one side wall of 120

the crank case, the diverging arms 43 of this lever having inward projections engaged in the groove 40 in a manner well known in the art. When the shipper lever is in the position shown in Fig. 1, the gear wheel 38 is brought into engagement with a driving gear wheel 44 which may be driven in any suitable manner from the engine of an automobile, and when the upper end of the shipper lever is moved to the right in Fig. 1 it will shift the lever out of said engagement. For the purpose of holding the shipper lever in either one of its adjusted positions the shipper lever is formed with a tooth or lug 45, as illustrated in Fig. 4, and attached to the thickened inner end of the arm 42 is a spring 46, the extremity of which is formed with two downwardly divergent corrugations 47 with which the lug or tooth 45 is adapted to respectively engage to hold the lever in its two adjusted positions. Of course, I do not wish to be limited to shifting the gear wheel 38, as a clutch might be used for engaging the gear wheel 38 with the shaft 8 and the gear wheel be continuously rotated by the wheel 44. I, however, prefer to shift the gear wheel 38 entirely out of engagement with the gear wheel 44, thus eliminating friction and conserving the power otherwise necessary to drive the wheel 38. As shown clearly in Fig. 1, the cylinder 10 is held upon the crank case by means of screws 48 which pass downward through ears 49 formed upon the base of the cylinder and entering upon the side walls of the crank case.

The advantages of my invention reside in the extreme simplicity of the pump and the fact that there are few parts in its construction.

A further advantage resides in the forming of the crank case in one integral piece instead of a plurality of pieces. This tends to strengthen the crank case, renders it more durable, renders it cheaper to make, and prevents the leakage of oil and dispenses with the necessity of packing the joints of the several sections with the consequent disadvantages due thereto.

Another particularly important element of my invention consists in the provision of the four fingers or guides 32 which serve to prevent the lateral motion of the depending portion of the piston. These fingers or guides prevent what is known as the "slap" of by keeping the motion entirely in a rectilinear direction, thus preventing the wear and weakening of the device from the side motion which would result without these guides. Without these guides the wear resulting from this pressure or slap will tend to produce leakage of the air with the corresponding inefficiency of the pump.

It is also to be noted that the pump may be very readily assembled. With the cylin-

der removed, the eccentric will be pressed on to the shaft in the crank case and the piston then dropped over the eccentric and fastened in position by pin 28. Thus the device may be assembled within a crank case composed of a single piece. It is obvious also that the parts of the pump may be readily disassembled. The cylinder is first disconnected from the crank case; the pin connecting the piston to the eccentric strap is then disconnected from the eccentric, the key 8^a removed, the shaft drawn out endwise, and the eccentric strap removed from the crank case. The cylinder may be readily removed from the crank case and replaced in a position again without any danger of losing the alignment of the piston with corresponding ill results. By removing the cylinder, the valve may be readily removed for grinding.

Another important feature which may be here noted is that as the cylinder is in one piece and as the opening through the guide 14 is milled out at the same time that the valve seat is formed, there is always perfect alignment of the valve with the valve seat and no chance for disalignment with its resulting imperfect fitting of the valve on the valve seat were the key for the stem 18 made in a separate piece fitted on to the cylinder.

While I have illustrated what I believe to be the preferable form of my invention, I wish it understood that many minor changes may be made without departing from the spirit of the invention as defined by the appended claims.

Having described my invention, what I claim is:

1. In a tire pump, a crank case, a cylinder detachably mounted upon the crank case, a shaft passing through the crank case, a piston having laterally disposed parallel depending spaced members longitudinally slotted to embrace the shaft, the slots opening at the lower ends of the members, whereby said depending members may be dropped into position over the shaft when the cylinder is removed, and an actuating member mounted on the shaft and disposed between said spaced members and operatively connected with the piston.

2. In a tire pump, a crank case, a cylinder detachably mounted upon the crank case, transverse shafts extending through the crank case, a piston having laterally disposed parallel depending spaced members, each member being longitudinally slotted to embrace the shaft, the slots opening at the lower ends of said members whereby to permit the members to be dropped into position over the shaft when the cylinder is removed, the side walls of the crank case having inwardly projecting portions with which said members have sliding contact to

thereby guide the said members and prevent lateral movement of the piston, and an actuating member disposed on the shaft and between said depending members and operatively engaged with the piston.

3. In a tire pump, a crank casing having inwardly projecting annular oppositely disposed flanges, a shaft having bearing in said flanges, a piston operating in the cylinder 10 and having oppositely disposed spaced parallel depending members, each slotted to snugly embrace the shaft, the outer faces of said members having sliding contact with the ends of the annular flanges, and an actuating member disposed on the shaft and between said depending members and operatively engaged with the piston.

4. In a tire pump, a crank case having oppositely disposed inwardly projecting annular bearing flanges, a shaft mounted therein, a cylinder on the crank case, a piston operating therein, and four depending fingers spaced from each other, there being 20 a pair of fingers on each side spaced from each other to snugly embrace the shaft, the outer faces of the oppositely disposed pairs of fingers having sliding engagement with the inner ends of the bearing flanges on the crank case, and an actuating member mounted upon the shaft and disposed between said 25

fingers and operatively connected at its upper end to the piston.

5. In a tire pump, a crank case having oppositely disposed inwardly projecting annular bearing flanges, a cylinder mounted 30 upon the crank case, a piston therein having oppositely disposed depending spaced members, each of said members being longitudinally slotted, a shaft passing through the bearings of the crank case and snugly 35 disposed on said slots of the depending members, the outer faces of the depending members having sliding engagement with the ends of the annular bearing flanges, an eccentric disposed upon the shaft and having its side faces slidably engaging the inner faces of the depending members, a ring carried upon the eccentric and likewise having its side faces slidably engaging the inner faces of the depending members, said ring having an extension pivotally connected to the outer ends of the depending members.

In testimony whereof I hereunto affix my signature in the presence of two witnesses. 45

HARRY W. LOCKLEY.
